ILLUMINATED WAND

Isadore B. Rachman, Philadelphia, Pa., assignor to
Metal Dynamics Corporation, Philadelphia, Pa.

Filed July 9, 1970, Ser. No. 24,218

Term of patent 14 years

Int. Cl. D29—99

U.S. Cl. D72—1

FIG. 1

FIG. 2

FIG. 3

FIG. 4

FIG. 5

FIG. 1 is a perspective view of an illuminated wand showing my new design;

FIG. 2 is a side elevational view thereof;

FIG. 3 is a rear elevational view thereof;

FIG. 4 is a top plan view thereof; and

FIG. 5 is a bottom plan view thereof.

The top of the wand is shaded to indicate translucency.

I claim:

The ornamental design for an illuminated wand, substantially as shown and described.
